UNITED STATES PATENT OFFICE

148,037

DESIGN FOR A TOY BOAT

Albert Rubenstein, Washington, D. C.

Application August 13, 1946, Serial No. 132,489

Term of patent 14 years

(Cl. D34—15)

To all whom it may concern:

Be it known that I, Albert Rubenstein, a citizen of the United States, residing at the city of Washington, in the District of Columbia, have invented a new, original, and ornamental Design for a Toy Boat, of which the following is a specification, reference being had to the accompanying drawing, forming a part thereof.

Figure 1 is a perspective view of a toy boat showing my new design.

Figure 2 is a perspective view showing the device inverted from the position shown in Figure 1.

I claim:

The ornamental design for a toy boat as shown.
ALBERT RUBENSTEIN.
